[57] CLAIM

The ornamental design for a display apparatus, as shown and described.

DESCRIPTION

FIG. 1 is a perspective view of a display apparatus in accordance with the invention.

FIG. 2 is a top plan view of the display apparatus of FIG. 1.

FIG. 3 is a bottom plan view of the display apparatus of FIG. 1.

FIG. 4 is an elevational view taken from one side of the display apparatus of FIG. 1.

FIG. 5 is an elevational view taken from the other side of the display apparatus of FIG. 1.

FIG. 6 is a front elevational view of the display apparatus of FIG. 1.

FIG. 7 is a rear elevation view of the display apparatus of FIG. 1.

FIG. 8 is a perspective view of another embodiment of a display apparatus in accordance with the invention.

FIG. 9 is a top plan view of the display apparatus of FIG. 8.

FIG. 10 is a bottom plan view of the display apparatus of FIG. 8.

FIG. 11 is an elevational view taken from one side of the display apparatus of FIG. 8.

FIG. 12 is an elevational view taken from the other side of the display apparatus of FIG. 8.

FIG. 13 is a front elevational view of the display apparatus of FIG. 8; and,

FIG. 14 is a rear elevational view of the display apparatus of FIG. 8.
